UNITED STATES PATENT OFFICE.

CYRUS CHAMBERS, JR., OF PHILADELPHIA, PENNSYLVANIA.

ENGINE-REGISTER.

SPECIFICATION forming part of Letters Patent No. 288,976, dated November 27, 1883.

Application filed April 13, 1881. (No model.)

To all whom it may concern:

Be it known that I, CYRUS CHAMBERS, Jr., of the city and county of Philadelphia, and State of Pennsylvania, have invented certain new and useful Improvements in Engine-Registers; and I do hereby declare that the following is a full, clear, and exact description of the invention, which will enable others skilled in the art to which it appertains to make and use the same, reference being had to the accompanying drawings, and to letters of reference marked thereon, which form a part of this specification.

Figure 1 is a front elevation of my improved register with the door removed. Fig. 2 is a transverse vertical section with the door closed. Fig. 3 is a similar section, showing the door prevented from closing by the displacement of a wheel-shaft. Figs. 4, 5, and 6 are diagrams showing the different relative positions of the flanged rims, spur-wheels, and driving-teeth as they rotate. Fig. 7 is a top view (detail) of the mechanism for rotating and holding the spur-gear, the pawl being shown in a position of rest before engagement with the gear. Fig. 8 is a similar view, showing the pawl thrown off from the spur-gear by the tooth following that which it has driven.

The same part is indicated by the same letter wherever it occurs in the drawings.

The object of my invention is to improve the construction of engine-registers by making the movements positive, preventing erroneous counting by holding the dial-wheels immovable except at the moment when they are required to make a tenth of a revolution in order to register a count, by giving certainty to the action of the driving and alarm mechanism, and by facilitating the setting of the machine and securing it against derangement and tampering.

The nature of my invention consists, first, in the permanent interlocking of the upper flanged rim of one wheel with the notches in the lower rim of the following wheel on the left, in such a manner that no wheel can be moved at any other time than that at which it is required to present a new digit and register a new count at the dial; second, in inclining the axes of the number-wheels at such an angle as will present all the digits to be read

through the openings of the dial in the same horizontal line; third, in the combination, with the interlocking wheels and their shafts, of the spur-wheels and driving-teeth, each 55 spur-wheel, except the "units" wheel, being driven by a tooth attached to the shaft of the wheel next on its right; fourth, in the use of a driving-pawl provided with a spring whose reaction serves the double purpose of throwing back the pawl both longitudinally and laterally to its initial position after each stroke, thus insuring the exact movement of one tooth of the driven gear at a time, unaffected by the lost motion of the pawl at either or both ends 65 of its stroke; fifth, in providing the door with perforations through which the numbers can be read, and with a plate or flange which, when the door is shut, lies on top of the wheel-shafts and prevents their being moved up, so 70 as to throw the wheels out of gear, and which also prevents the door from being shut unless all the shafts are in proper position and the wheels interlocked; sixth, in providing the shaft of any one of the number-wheels with a 75 double tappet cam, which at any predetermined count shall engage with a bell-arm and give an alarm.

In the drawings, A marks the bed-plate of the machine, which supports a quadrangular 80 case, C, in which the registering mechanism is contained. This case is closed by a door, D, hinged at bottom, perforated with a row of openings, O, through which the registered numbers are read. This door is also provided 85 with a projecting plate, p, which, when the door is closed, passes under a flat spring, d, which holds it by friction. On the top of the case is a bell, B, which serves to give an alarm when struck by the hammer h, attached to the 90 shaft b, which is operated so as to bring the hammer against the bell by means of a spring and arm. (Not shown.) On the hammer-shaft b is an arm, a, which engages at a pre-determined count with a cam, c, on the shaft 95 of one of the dial or number wheels.

Inside of case C is a cast frame, F, made in halves, which supports the registering mechanism. This frame is provided with lugs 7 above and below, which serve as journal-boxes 100 for the shafts s s of the index-wheels. These shafts are inclined, as shown, for the purpose

of bringing the digits of the dial-wheels into a horizontal line, when presented for reading to the dial-openings. The dial-wheels are fixed to their shafts, and these are provided near their lower ends with spur-gears G, each having ten teeth, and with single teeth or detents *t*, placed above the spur-gears, and which at each entire revolution of the dial-wheel engage with the gear on the next shaft to the right, and turn it one-tenth of a revolution. The dial-wheels are in the present example five in number; but the series may be indefinitely extended to meet the requirements of any case. The wheel U on the right is the "units" wheel. The next to the left, T, is the "tens" wheel; H, the "hundreds," M the "thousands," and X the "ten thousands" wheel. Each wheel has a flanged rim, *r*, whose upper edge interlocks at all times with notches *n* in the lower edge of the rim of the wheel immediately to the left of it. There are no notches on the lower edge of the rim of wheel U, and the upper edge of the rim of wheel X (the last of the series) is plain. The manner in which the upper edges of the flanged rims interlock with the notches of the wheels on the left is illustrated by the diagrams Figs. 4, 5, and 6. The arrows indicate the direction in which the wheels are turning. The heavy lines in these figures mark the unbroken part of the rim *r*; *o o*, the openings in it, and *n n* the notches on the lower edge of the adjacent wheel. In Fig. 6 the solid rim of wheel U is shown as engaged or interlocked with two notches *n* of wheel T, an intermediate notch *n* being within the rim *r*, the interlocking space being equal to that occupied by three notches. When the relative positions of the wheels are those shown in this figure, wheel T is incapable of rotation. Fig. 5 shows the rim *r* of wheel U in position to allow wheel T to move one notch, or one-tenth of a revolution, the rim *r* being cut away at the openings *o o*, to allow the notched rim to move without obstruction. The instant wheel T has moved one-tenth of a revolution the rim *r* is brought into the position shown in Fig. 4, and prevents any further movement until wheel U has made another revolution. The positions of the driving-teeth *t* in the various positions of the wheels U T are clearly shown, Fig. 5 showing the tooth in engagement with the gear G, and at the moment of driving it, while the openings *o* are in position to allow wheel T to make the required movement.

The unit-wheel U is steadied by the spring-detent *g*, and is driven by the reciprocation of spring-pawl P, a flat plate of the shape shown in Fig. 1, attached to a rod, R, playing in eyes *e e* in the lower part of frame F. (See Figs. 1, 7, and 8.) A spiral spring, S, is wound around rod R, and attached by one end to it at the point *i*. The free end abuts against an eye *e*, and the longitudinal reaction of the spring tends to drive the pawl against the case C to the position shown in Fig. 1. The

lateral reaction of the spring impels the pawl P inward toward the face of frame F. The rod R is connected with the machinery whose movements are to be counted by the link L 70 in any convenient manner.

The shafts *s* can be raised in their journal-boxes sufficiently to unlock and readjust the number-wheels whenever required. When properly arranged and in place, the plate *p* of 75 the door rests upon their upper ends and prevents them from being accidentally or intentionally unlocked and changed in relative position.

The operation of the machine is as follows: 80 The wheels, at the outset, are all set at zero. By the first stroke of the engine or other machine whose movements are to be counted, the rod R is drawn out till cam P impinges against the first tooth of the gear G of units-wheel U, and moves that wheel one-tenth of a revolution, presenting the digit 1 at the right-hand opening of the door or dial D. Nine strokes of pawl P bring the rim of wheel U into the position to allow of the movement 90 of wheel T, and the tooth *t* into the position to impart that movement at the tenth stroke. The cipher (0) then comes opposite the right-hand opening of the dial and the digit 1 opposite the second opening. The entire revolution 95 of any one wheel produces one-tenth of a revolution of the next wheel on the left, according to the ordinary method of operating register mechanism. As soon as the pawl P has carried one tooth of gear G a tenth of a revolution, the succeeding tooth pushes the pawl outward and allows it to pass forward without producing any further movement of the gear. It is then driven back by spring S to its initial position, and inward by the lateral reaction 100 of the spring against the face of frame F and into line for the next stroke.

The double tappet bell-cam is set for giving an alarm at any particular point in the count by attachment to the shaft of the wheel that registers that count in such a position as to engage the arm of the shaft *b* at the proper moment to cause it to draw back the bell-hammer *h* to give the alarm-stroke.

Having thus fully described my invention, 115 what I claim, and desire to secure by Letters Patent, is—

1. In a registering-machine, a series of number-wheels fixed upon inclined parallel shafts, and provided with interlocking flanged rims, 120 all constructed and operating in the manner and for the purpose described.

2. In combination with the inclined shafts *s* and interlocking flanged rims of the number-wheels of a registering-machine, the spur-gears 125 G and driving-teeth *t*, arranged and operating as and for the purpose specified.

3. The combination of the rod R, eyes *e e*, spring S, having the double reaction described, and pawl P, all constructed, arranged, and operating in the manner and for the purpose de- 130 scribed.

4. In combination with the door D, the flange p and spring d, the flange being located relatively to the shafts s in the manner specified, for the purpose stated.
5. The combination, with the shaft s of a number-wheel, of the double tappet cam c, arm a, shaft b, hammer h, and bell B, all arranged and operating as and for the purpose specified.
- 10 6. In a registering-machine, a series of dial or number wheels provided with flanged rims, as described, the upper flanged rim of one wheel interlocking with notches in the lower flanged rim of the next wheel on its left, for the purpose of rendering each wheel immovable at all times except when its movement is required to indicate a change in the count, all substantially in the manner set forth.
7. In a registering-machine, the inclined dial-wheels having figures inscribed upon them in a vertical position, in combination with the dial-plate D, having a horizontal line of perforations, O, as and for the purpose stated.
- In testimony that I claim the foregoing as my own invention I affix my signature in presence of two witnesses.
